Application filed April 16, 1927. Serial No. 21,619. Term of patent 3½ years.

To all whom it may concern:

Be it known that I, TAUBE DAVIS, a citizen of the United States, and a resident of the city of New York, borough of Manhattan, in the county and State of New York, have invented a new, original, and ornamental Design for Dress, of which the following is a specification, reference being had to the accompanying drawing, forming part thereof, wherein the dress is distinguished by a comparatively wide tucked band near

the center having edges formed with a series of pointed projections.

Figure 1 is a front view of a dress, showing my new design, the same being illustrated on a figure.

Figure 2 is a rear view of the dress shown in Figure 1.

I claim:

The ornamental design for a dress, substantially as shown and described.

TAUBE DAVIS.
